UNITED STATES PATENT OFFICE.

FRANCES K. FISCHER, OF BROOKLYN, NEW YORK.

BABY CARRIAGE, GOCART, AND THE LIKE.

Application filed January 12, 1922, Serial No. 528,620. Renewed December 21, 1926.

My present invention relates to improvements in baby-carriages, go-carts, and the like, and aims to provide a construction for devices of the character specified wherein the same are provided with convenient and readily accessible, available and removable toilet appliances for the use of the infant in the device. It is an object of the present invention to provide a construction for devices of the character referred to which shall have the toilet appliance, such as a commode, so built into the device as to require very little change in the process of manufacturing the same according to the methods hitherto employed by the leading manufacturers of such devices, and which shall, at the same time, be economical and simple in construction, and highly convenient and accessible for use and removal.

In the accompanying specification I have described, and in the annexed drawings shown, a preferred embodiment of my present invention in the form of a baby-carriage, it being, however, clearly understood that my invention is not limited to the particular embodiment thereof herein shown and described for purposes of illustration only.

Referring to the drawings,

Figure 1 is a longitudinal section, partly in elevation, of the baby-carriage as a whole;

Figure 2 is a top plan view of the same, the commode having been removed;

Figure 3 is a fragmentary, detail view, in perspective, showing one of the false bottoms constructed and arranged for sliding in its frame;

Figure 4 is a perspective view of the commode with its cover in raised position; and

Figure 5 is a fragmentary, sectional view of the commode with its sealed cover in place.

Before describing in detail the illustrative embodiment of the present invention referred to above, it may be advisable briefly to point out the purposes and objects of the present invention as embodied in the devices referred to above, and the defects of the devices hitherto intended to fulfil the same end, which defects are substantially entirely avoided by the present invention. In the baby-carriages, go-carts, and the like, hitherto intended and designed to include a toilet appliance, the inclusion of the toilet appliance, such as a commode, has necessitated such a fundamental alteration in the construction of the devices over the ordinary

construction of such devices when without any toilet appliance, as to make such devices very expensive to manufacture, and impractical and inconvenient in use.

These disadvantages are largely, even entirely, overcome by the present invention.

Referring to the illustrative embodiment mentioned above, the same may comprise a carriage body 10, of which the lower portion 11, which may or may not comprise a continuation of and be integral with the upper portion 12 of the body portion, provides a bottom 13, above and spaced from which is a false bottom, generally indicated by the reference character 14.

The carriage, generally indicated by the reference character C, comprises the usual front wheels 15, the rear wheels 16, the shafts 17 and 18, and the frame 19, the upper portion of which may comprise a handle or other device 20 for manipulating the baby-carriage.

It is, of course, to be understood that where the device is applied to go-carts, or similar vehicles, instead of to baby-carriages, the construction will be correspondingly altered, although the present invention is successfully applicable to go-carts, and the like, as well as to baby-carriages.

Beneath the false bottom 14 is a partition 21 providing a forwardly disposed receptacle 22 and a rearwardly disposed receptacle 23. The forwardly disposed receptacle 22 is provided with a movable, preferably a sliding, cover 24 for covering or uncovering an opening 25 in the false bottom 14 directly over the receptacle 22 which is intended to contain, for convenient access, various articles which the infant may require. The cover 24 slides in a groove or slideway 26 provided by a frame or other suitable means 27, as shown more clearly in Figure 3 of the drawing.

The rearwardly disposed receptacle 23, which is intended and designed to house and contain the commode or other toilet appliance intended for the use of the infant, is also provided with a movable, preferably a sliding, cover 28 for the opening 29 in the rear portion of the false bottom 14. This movable cover 28 is intended to expose or cover, as desired, the opening 29 through which access may be had to the commode, generally designated by reference character 30. The cover 28 is provided with a substantially circular opening 28a into which fits

a cover 28^b provided with a bail or handle 28^c, the opening 28^a being immediately above the commode 30 when the cover 28 is in closed position. The cover 28 slides in a groove or 5 slideway 31 provided by the rear portion 32 of the frame 27.

The rear portion of the carriage body 10 is provided with a hinged end cover or closure 33 hinged at 34 to the carriage body 10 10 and provided with a catch or other suitable locking means 35 to provide access to the receptacle 23 for removing or replacing the commode 30.

Means are provided for suitably retaining 15 the commode 30 in position within the receptacle 23 during the movement of the baby-carriage C. For this purpose, I provide the spring arms 36 which yieldingly receive the commode 30 and are attached to a hollow, 20 cylindrical sleeve or bracket 37 through which passes a guide rod 38, the ends of which ride within the arcuate guide grooves 39. The bracket 37 and the guide rod 38 are provided with the two arms 40, through the 25 lower perforated ends of which the guide rod 38 passes. The upper ends of the arms or brackets 40 are similarly perforated and are carried by a supporting rod 41 suitably supported in the bearings 42. A spring 43 is 30 provided, one end of which is fixedly carried by the partition 21, and the other end of which bears against a projection 44 forming a part of the sleeve or bracket 37.

The commode 30 is preferably provided 35 with a sealed cover 45 which in turn, is provided with a bail or handle 46 for manipulating the same. The commode is also provided with a handle 47 for facilitating its manipulation into and out of the commode 40 receptacle.

The use and manipulation of the device described above are substantially as follows: When it is desired to place an article for the use of the infant, or for some other purpose, 45 within the forwardly disposed receptacle 22, or to remove any article therefrom, the slideable cover 24 is manipulated so as to expose the opening 25. It will be noted that the slideable cover 24 is positioned above the slideable cover 28, so that the two covers will clear each other when both openings 25 and 50 29 are exposed, although the cover 24 may, if desired, be placed below the cover 28.

When it is desired to place the commode 55 within the rearwardly disposed receptacle 23, the hinged end closure 33 is raised, and the commode 30, provided with the sealed cover 45 carrying the bail 46, is placed within the receptacle 23 and snapped into position within the spring arms 36 which serve to retain the commode in position during any movement of the baby-carriage or similar device 60 to which the present invention may be applied.

65 Due to the provision of the sleeve or

bracket 37, the guide rod 38, the ends of which ride in the slides or grooves 39, the arms 40 pivotally carried by the rod 41 and themselves pivotally supported on the guide rod 38 about which the sleeve or bracket 37 70 has a pivotal movement, and the spring 43, the commode 30 is supported in such a manner that it may have a certain amount of free movement with its weight in part at least spring-supported. 75

When it is desired to expose the commode 30 for use, the slideable cover is forwardly slided in the groove 31 to expose the opening 29, or the cover 28^b is removed. Thereupon, the sealed cover 45 may be removed and the device used, after which the sealed cover is put back into place, and the slideable cover 28 rearwardly moved to cover the opening 29 or the cover 28^b replaced. 80

The advantages of the present invention, 85 as embodied in the illustrative device described above, are numerous and of great practical importance. Due to the arrangement of parts described above, a construction of baby-carriage, go-cart, or the like, is provided which requires little fundamental alteration of the construction hitherto employed for the manufacture of such devices, while at the same time rendering possible the incorporation in the device of a toilet appliance, such as a commode, in a simple and convenient manner and at the same time providing for the easy and accessible use and removal of such toilet appliances. At the same time the provision of the end closure 100 permits the ready removal and replacement of the commode with its sealed cover at any time desired, the whole arrangement being an extremely practical one, easy and economical to manufacture, and entirely satisfactory 105 and convenient in use.

It is, of course, to be understood that my invention is not limited to the illustrative embodiment thereof herein shown and described for purposes of illustration only. 110

What I claim is:

1. In a baby-carriage, go-cart, or the like, a false bottom having a slideable cover portion, a commode receptacle positioned beneath said false bottom and adapted to be exposed or covered by the slideable cover portion of said false bottom, as desired, a commode within said receptacle, and means for retaining said commode in position within said receptacle. 115

2. In a baby-carriage, go-cart, or the like, a false bottom having a slideable cover portion, a commode receptacle positioned beneath said false bottom and adapted to be exposed or covered by the slideable cover portion of said false bottom, as desired, a commode within said receptacle, and spring means for retaining said commode in position within said receptacle. 125

3. In a baby carriage, go-cart, or the like, 130

a carriage body, a true bottom therefor, and a false bottom thereabove, a pair of frames on said false bottom, slideways in said frames, and a pair of slidable covers in said slideways, the slideways being arranged 5 one above the other, so that the covers may be placed in juxtaposition one above the other to uncover one or more receptacles underneath the false bottom.

10 4. In a baby carriage, go-cart or the like, a receptacle provided with an opening, and a commode-retaining device within said receptacle, said device having resilient arms and resilient means for supporting said 15 resilient arms.

5. In a baby carriage, go-cart or the like, a receptacle, an opening for said receptacle, and a commode-retaining device within said receptacle, said device comprising a shaft,

arms secured to and depending from said 20 shaft, said arms securing a guide rod, a bracket on said guide rod, commode-retaining means on said bracket and resilient means urging said commode-retaining device in 25 one direction.

6. In a baby carriage, go-cart or the like, a receptacle, an opening for said receptacle, and a commode-retaining device within said 30 receptacle, said device comprising a shaft, arms secured to and depending from said shaft, and a guide rod secured by said arms, arcuate grooves being provided in the side of said guide rod, and said guide rod having ends extending into said arcuate grooves.

In testimony whereof, I have signed my 35 name to this specification this 21st day of December, 1921.

FRANCES K. FISCHER.
